UNITED STATES PATENT OFFICE.

OSWALD H. HANSEN, OF PORT WASHINGTON, WISCONSIN.

INTERNAL-COMBUSTION ENGINE.

Application filed August 28, 1920. Serial No. 406,580.

This invention relates in general to improvements in the construction and operation of fluid pressure actuated motors, and relates more specifically to an improved 5 valve mechanism for internal combustion engines and the like.

An object of the invention is to provide an improved fluid pressure actuated motor such as an internal combustion engine, which 10 is simple in construction and efficient in operation. Another object is to provide simple and efficient valve mechanism for controlling the admission and exhaust of fluids to and from a fluid pressure actuated 15 engine.

Some of the more important specific objects of the invention are as follows:—

To reduce to a minimum the noise and vibration in a motor, by eliminating the use 20 of cams, levers and reversely movable parts.

To provide exceedingly simple, compact and highly efficient valve gear all parts of which are readily accessible for inspection or adjustment, and which may be conveniently assembled or dismantled. 25

To make provision for rapid, precise and independent adjustment of the inlet and exhaust valves of a fluid pressure actuated motor, whereby the time of opening and 30 closing of the valves may be relatively varied to produce most efficient operation of the engine.

To provide a rotary valve whereon the 35 pressures are automatically balanced and which may be effectively lubricated and packed to positively prevent escape of fluids under pressure.

To secure desirably large port areas and 40 to provide for rapid opening and closing of the inlet and exhaust ports.

To avoid delivery of exhaust gases through the inlet passages and vice versa; and to prevent excessive heating of the engine parts.

To facilitate commercial manufacture by 45 simplifying the various parts and making them readily machinable with standard machine tools.

To provide various other improvements in 50 the construction and operation of engines of the internal combustion type and especially motors for driving high speed vehicles for land, water and air.

The present invention contemplates improvements over the structures disclosed in Patent Number 1,220,814, granted March 27, 1917.

A clear conception of an embodiment of the invention and of the operation of an internal combustion engine employing the principles thereof, may be had by referring 60 to the drawing accompanying and forming a part of this specification, in which like reference characters designate the same or similar parts in the various views.

Fig. 1 is a part sectional top view of two 65 adjacent cylinders of a vertical four cylinder internal combustion engine, with the head removed and showing independent rotary inlet and exhaust valves for controlling the flow of fluids to and from the engine. 70

Fig. 2 is a fragmentary transverse vertical section through the internal combustion engine, the section being taken at the inlet valve and along the irregular line II—II of 75 Fig. 1.

Fig. 3 is a fragmentary transverse vertical section through the internal combustion engine, the section being taken at the exhaust valve and along the line III—III of Fig. 1. 80

Fig. 4 is a diagrammatic illustration of the valve driving gearing drawn to a reduced scale.

The internal combustion engine illustrated in the drawing, comprises in general, a plurality of working cylinders 2 arranged in pairs, a set of independent rotary cylindrical inlet and exhaust valves 3, 4 for each pair of cylinders, a detachable cylinder head 5 coacting with each pair of cylinders and 85 with the corresponding set of valves, and suitable mechanism for driving the valves 3, 4. The cylindrical inlet valve 3 is adjustably secured to the upper extremity of the vertical shaft 14, by means of a nut 25. The 90 cylindrical exhaust valve 4 is adjustably secured to the upper extremity of the vertical shaft 15, by means of a nut 26. The shafts 14, 15 are supported in suitable bearings in the engine frame and are provided at their 95 lower extremities with helical gears 21, 22 respectively, see Fig. 4. The gears 21, 22 mesh with opposite sides of a common helical driving gear 23 secured to the crank shaft 100

24 of the engine, thus providing for rotation of the valves 3, 4 in opposite directions as indicated by the arrows in Fig. 1.

The valves 3, 4 lie within cylindrical recesses in the ends of the cylinders 2, and have opposed faces which lie in common planes. The lower face of the inlet valve 3 is in open communication with the combustion chamber 6 of each cylinder 2 through inlet ports 7. The upper face of the inlet valve 3 is in open communication with the combustion chamber 6 of each cylinder 2 through inlet ports 9 formed in the cylinders and through ports 19 formed in the cylinder head 5. The lower face of the exhaust valve 4 is in open communication with the combustion chamber 6 of each cylinder 2 through exhaust ports 8. The upper face of the exhaust valve 4 is in open communication with the combustion chamber 6 of each cylinder 2 through ports 10 formed in the cylinders and through ports 20 formed in the cylinder head 5. The ports 7, 8, 9, 10, 19, 20 are all of equal cross sectional area. Annular packing rings 17 engage the faces of the valves 3, 4 adjacent to each of the ports 7, 8, 19, 20, these rings being located in recesses in the cylinders 2 and head 5, and being urged against the valve surfaces by means of helical compression springs.

The inlet valve 3 is hollow and has a single central inlet port which is in open communication with the inlet supply passage 11 formed in the cylinder head 5. The passage 11 is surrounded by an annular packing ring 16 which engages the upper face of the valve 3, the ring 16 being located within a recess in the head 5 and being urged against the surface of the valve 3 by means of a helical compression spring. The inlet valve 3 is also provided with oppositely disposed eccentric delivery ports 27 of like form and size, which communicate with the supply passage 11 through the inner chamber of the valve 3, and which are adapted to intermittently establish communication between the interior of the valve 3 and the ports 7, 19, during rotation of the valve.

The exhaust valve 4 is hollow and has a pair of oppositely disposed eccentric exhaust openings 28 of like form and size, which communicate with the inner chamber of the valve 4 and which are adapted to intermittently establish communication between the interior of the valve 4 and the ports 8, 20, during rotation of the valve. The interior chamber of the exhaust valve 3 is in open communication with the exhaust passages 12 through an opening in the side of the valve 4.

The cylinders 2 of the engine are provided with cooling water jackets 18, of usual construction which communicate with suitable jackets in the head 5. Each of the cyl-

inders 2 is also provided with an opening 13 within which an ignition device of usual form may be located. Other details necessary to complete the structure and which form no part of the present invention, have been omitted in order to avoid obscurity.

During the normal operation of the engine, the crank shaft 24 is being rotated by the reciprocating pistons located within the cylinders 2. Rotation of the crank shaft 24 is transmitted through the helical gears 23, 22, 21, and through the vertical valve shafts 15, 14 to the valves 4, 3, causing the valves to rotate in opposite directions as indicated by the arrows in Fig. 1. The timing of the valves 3, 4 is such that during the suction stroke, the eccentric ports 27 of the inlet valve 3 are in open communication with the inlet ports 7, 19, 9 thereby permitting vapor fuel to be drawn into the combustion chamber 6 from the supply passage 11 through the interior of the valve 3 and the ports 27, 7, 19, 9. As disclosed in Fig. 1, the inlet valve 3 is about to open in order to admit fuel to the cylinder 2 at the right, the exhaust ports of this cylinder having just been closed. During the exhaust stroke, the eccentric ports 28 of the exhaust valve 4 are in open communication with the exhaust ports 8, 20, 10 thereby permitting spent gases to be delivered from the combustion chamber 6 through the ports 8, 10, 20, 28 and the interior chamber of the valve 4, and from thence through the side opening in the valve 4 to the exhaust passages 12. As disclosed in Fig. 1, the exhaust valve 4 has closed with respect to the cylinder 2 at the right and has opened with respect to the cylinder 2 at the left. During the compression and expansion strokes, both valves 3, 4 are closed, ignition and combustion of the gases taking place during these strokes. The cylinders 2 are preferably arranged in sets of four having pistons and connecting rods associated with cranks advanced ninety degrees relatively to each other, and provided with one set of inlet and exhaust valves 3, 4 for each pair of cylinders. With this arrangement, one cylinder 2 is under suction, another is under compression, another is under expansion, while the other is under exhaust, the sequence of events in each cylinder for two complete revolutions of the crank shaft, being in the order mentioned.

It will be noted that all elements of the valve mechanism are continuously rotatable in the same direction and that the use of cams, levers and reversely movable parts has been eliminated. With such a structure, the power necessary for operation of the mechanism is reduced to a minimum and noise and vibration are entirely eliminated.

If it is desired to relatively adjust the valves 3, 4, it is necessary only to remove the cylinder head 5, to loosen the adjust-

ing nut 25, 26 of the valve which it is desired to adjust, and to rotate the loosened valve about its operating shaft 14, 15 the desired amount, after which the adjusted 5 valve may again be secured to its shaft by tightening the nut 25, 26. It will be obvious that the adjusting means may also be located near the driving gears 21, 22 instead of at the valves 3, 4 as disclosed.

10 With the cylinder head 5 removed, the valves 3, 4 and other internal elements of the engine are readily accessible for inspection and removal. The mechanism is reduced to simple and compact form thereby 15 by making an engine embodying the same especially desirable for the propulsion of vehicles such as automobiles and airplanes.

The disposition of the inlet and exhaust ports 7, 8, 9, 10, 19, 20 and the provision of 20 packing rings 17 surrounding the ports adjacent to the valve surfaces, produces automatic balancing of the pressures upon the valves 3, 4 during rotation thereof, thereby also minimizing the power necessary for 25 actuation and avoiding undesirable pressure on the bearings. The packing rings 16, 17 also prevent escape of fluids under pressure and permit ready lubrication of the bearing surfaces.

30 By placing the valves 3, 4 in rolling peripheral association with each other and on opposite sides of the common plane of the cylinder axes, the valves may be made as large as desired in order to secure large 35 port areas, and the proportioning of the driving gears 21, 22, 23 may be made such that rapid opening and closing of the valves results. By providing independent inlet and exhaust valves 3, 4 necessity of 40 delivering the inlet fluids through the relatively hot exhaust ports, is avoided, thereby eliminating danger of preignition. The rotary cylindrical valves 3, 4 also permit location of relatively large cooling jackets 45 in close proximity to the heated surfaces thereby permitting efficient cooling of the parts.

As all of the valve elements are formed 50 as bodies of revolution, having either plane surfaces or surfaces of revolution, these elements are readily machinable with standard tools such as planers, lathes and boring mills, thereby reducing to a minimum the cost of manufacture.

55 It should be understood that it is not desired to limit the invention to the exact details of construction herein shown and described, for various modifications within the scope of the appended claims may occur to persons skilled in the art.

It is claimed and desired to secure by Letters Patent:—

60 1. In combination, a pair of working cylinders, a hollow inlet valve for controlling admission of fluid to both of said

cylinders, means for admitting fluid centrally to said valve and eccentrically therefrom to said cylinders, a hollow exhaust valve for controlling delivery of fluid from both of said cylinders, and means for delivering fluid from said cylinders eccentrically to said valve and laterally from the side thereof. 70

2. In combination, a pair of working cylinders, an inlet valve for alternately admitting fluid to said cylinders, means for admitting fluid centrally to said valve and eccentrically therefrom to said cylinders, an exhaust valve for alternately delivering fluid from said cylinders, and means for delivering fluid from said cylinders eccentrically to said valve and laterally from the side thereof. 75

3. In combination, a pair of working cylinders having parallel axes, a hollow inlet 80 valve rotatable about an axis parallel to the axes of said cylinders, means for admitting fluid centrally to said valve and eccentrically therefrom to both of said cylinders, a hollow exhaust valve rotatable about an axis parallel to the axes of said cylinders, and means for delivering fluid from said cylinders eccentrically to said valve and laterally from the side thereof. 90

4. In combination, a pair of working cylinders having parallel axes, an inlet valve rotatable about an axis parallel to the axes of said cylinders, means for admitting fluid centrally to said valve and eccentrically from an end thereof to said cylinders, an exhaust valve rotatable about an axis parallel to the axes of said cylinders, and means for delivering fluid from said cylinders eccentrically through an end of said valve and laterally from a side thereof. 95

5. In combination, a working cylinder, a hollow inlet valve for controlling admission of fluid to said cylinder, means for admitting fluid centrally to said valve and eccentrically therefrom to said cylinder, a hollow exhaust valve for controlling delivery of fluid from said cylinder, and means for delivering fluid from said cylinder eccentrically to said valve and laterally from the side thereof. 100

6. In combination, a working cylinder, a hollow inlet valve rotatable about an axis parallel to the axis of said cylinder, means for admitting fluid centrally to said valve and eccentrically from said valve to said cylinder, a hollow exhaust valve rotatable about an axis parallel to the axis of said inlet valve, and means for delivering fluid from said cylinder eccentrically to said valve and laterally from the side thereof. 115

7. In combination, a pair of working cylinders located closely adjacent to each other, a rotary inlet valve common to both of said cylinders, means for admitting fluid centrally to an end of said valve and eccentrically from both ends thereof to said cylinder. 120

inders, a rotary exhaust valve common to both of said cylinders, and means for delivering fluid from said cylinders eccentrically through both ends of said valve and laterally from a side thereof.

8. In combination, a pair of working cylinders, an inlet valve for alternately admitting fluid to said cylinders, means for admitting fluid centrally to said inlet valve and eccentrically therefrom to said cylinders, an exhaust valve for alternately delivering fluid from said cylinders, means for delivering fluid from said cylinders eccentrically to said exhaust valve and laterally from the side thereof, and means for rotating said valves in opposite directions about axes parallel to the axes of said cylinders.

9. In combination, a pair of working cylinders, a rotary inlet valve for alternately admitting fluid to said cylinders, means for admitting fluid centrally to said inlet valve

and eccentrically therefrom to said cylinders, a rotary exhaust valve for alternately delivering fluid from said cylinders, said valves having peripheral engagement, and means 25 for rotating said valves in opposite directions and at the same peripheral speed.

10. In combination, a pair of working cylinders, a rotary inlet valve for alternately admitting fluid to said cylinders, a rotary 30 exhaust valve for alternately delivering fluid from said cylinders, means for delivering fluid from said cylinders eccentrically to said exhaust valve and laterally from the side thereof, said valves having peripheral engagement, and means for rotating said valves in opposite directions and at the same peripheral speed. 35

In testimony whereof, the signature of the inventor is affixed hereto.
